INVENTOR,
J. C. Parker,
BY *Munn & Co.*

ATTORNEY,

UNITED STATES PATENT OFFICE.

JAMES C. PARKER, OF WOODSTON, KANSAS.

DESK-SIGNAL.

SPECIFICATION forming part of Letters Patent No. 391,185, dated October 16, 1888.

Application filed April 12, 1888. Serial No. 270,425. (No model.)

To all whom it may concern:

Be it known that I, JAMES C. PARKER, of Woodston, in the county of Rooks and State of Kansas, have invented a new and Improved 5 Desk-Signal, of which the following is a specification, reference being had to the annexed drawings, forming a part thereof, in which—

Figure 1 is a perspective view of my improved signal, and Fig. 2 is a perspective view 10 of a modified form of the same.

Similar letters of reference indicate corresponding parts in both views.

The object of my invention is to provide a simple and effective signal to be used by 15 scholars in schools for attracting the attention of the teacher.

The invention consists in the peculiar construction and arrangement of parts, as herein-after fully described, and pointed out in the 20 claim.

The support A, in which the signal-arm B is pivoted, is formed of a plate doubled or returned parallel with itself, and provided with flanges C for attachment to the desk-top. A 25 part of the curved portion of the plate is cut away to admit the arm B between the folds of the plate A and to form a shoulder, a, for stopping the arm B after it has passed a vertical position. The arm B turns on a pivotal pin, 30 b, passing through the plate A and through the portion of the arm received between the folds of the plate.

The signal shown in Fig. 2 is designed to be placed against the front or end of the desk. The supporting-plate A' in this case is of L-shaped 35 section, a portion of the flanges of which is cut away to form a shoulder, a', for stopping the arm B, the arm B being connected with the plate A' by a rivet, b'. To the top of the desk is secured a soft pad, D, of rubber or other 40 suitable material, for the arm B to strike upon when lowered, the object being to avoid noise.

When a signal is to be given, the scholar lifts the arm B from the position shown in dotted lines into the position shown in full 45 lines; and it is allowed to remain in this position until a reply is secured, when it is lowered into a horizontal position, as indicated by dotted lines.

Having thus described my invention, I claim 50 as new and desire to secure by Letters Patent—

An improved signal for school-desks, consisting of the support A, formed of a plate doubled upon itself and its ends bent outward to form flanges C, and having its curved portion cut away to form the shoulder a, and the arm B, pivoted in the cut-away portion and engaging the shoulder thereof when in a vertical position, substantially as herein shown and described. 55

JAMES C. PARKER.
